Primary Examiner — Manpreet S Matharu*Assistant Examiner* — Mojtaba Tehrani(74) *Attorney, Agent, or Firm* — Mayback + Hoffman, P.A.; Gregory L. Mayback(57) **CLAIM**

The ornamental design for an antenna alignment device, as shown and described.

DESCRIPTION

FIG. 1 is a right rear perspective view of an antenna alignment device, showing my new design;

FIG. 2 is a left rear perspective view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front elevation view thereof; and,

FIG. 8 is a rear elevation view thereof.

The broken lines in the figure drawings represent unclaimed portion of the design only and form no part of the claim.

1 Claim, 3 Drawing Sheets(56)
